CLAIM

The ornamental design for a heater grill, as shown and described.

DESCRIPTION

FIG. 1 is a rear view of the heater grill according to my new design;

FIG. 2 is a front view of the heater grill of FIG. 1;

FIG. 3 is a perspective view of the heater grill of FIG. 1;
FIG. 4 is a left side view of the heater grill of FIG. 1, the
right side view being a mirror image thereof; and,
FIG. 5 is a top view of the heater grill of FIG. 1, the bottom
view being a mirror image thereof.
